SCARFLIKE COVERING

Toby Katzman and Abraham M. Katzman,
Long Beach, N. Y.

Application February 6, 1941, Serial No. 377,590

2 Claims. (Cl. 2—91)

This invention relates generally to wearing apparel and is more particularly a scarf-like covering.

It is one of the main objects of this invention to provide a scarf-like covering which due to its construction, shape and proportions is convertible into different styles of wearing apparel, such as blouses, beach suits, etc.

It is another object of the present invention to provide a scarf which is substantially U-shaped and comprises a collar portion and relatively long extensions from said collar portion constituting means for draping and arranging about parts of the human body.

Still another object of the present invention is to provide a scarf which lends itself readily to be converted into varying shapes, as for example by knotting the extensions and looping the latter through collar portion of said scarf.

A still further object of the present invention is to provide a scarf adapted for use by both the male and female sex and which may be provided in various plain and contrasting colors, and which may have plain or ornamental edges, in particular at the collar portion.

Yet, another object of the present invention is to provide a scarf or similar wearing apparel which is made of any desired material, such as silk, wool and the like, and which can be worn over the clothing as a tie, or other covering, or as a decorative supplement to a garment.

These and other objects and advantages of the invention will appear from the following disclosure thereof together with the attached drawing which illustrates certain forms of embodiment thereof. These forms are shown for the purpose of illustrating the invention since the same has been found in practice to give satisfactory and reliable results, although it is to be understood that the various parts of which the invention consists can be variously arranged and organized and that the invention is not limited to the precise arrangement and organization of the instrumentalities as herein shown and described.

Fig. 1 is a top plan view of a convertible scarf made in accordance with the invention.

Fig. 1a is a detailed view of a corner of the collar portion of the scarf of Fig. 1.

Fig. 2 is a scarf made according to the invention in a modified form.

Fig. 3 is an illustration of one of the above-mentioned scarfs with knotted extensions.

Figs. 4 to 6 inclusive illustrate different modes into which the scarf may be converted.

Referring now more particularly to the drawing there is disclosed in Fig. 1 a scarf 30 having a collar portion 31 and extended bifurcations 32, 33, the latter forming extensions of collar 31 and being preferably considerably longer than the same. The extensions 32, 33 terminate into respective edges 32a, 33a and are formed by a slit or slot 34 in the scarf material, the edges of which bordering the slot 34 being finished with 10 stitches 35.

Collar portion 31 is preferably made slightly narrower than the combined width of the extensions 32, 33 and slot 34. The outer boundary 36 of the scarf is finished off with stitches 31. 15 Adjacent the corners 38, 39 of the collar portion 31 there may be provided loops 40, 41 for a purpose hereinafter set forth.

In Fig. 2 the convertible scarf 42 has the collar portion 43, the extensions 44, 45 terminating into respective edges 44a, 45a, the extensions being separated by the longitudinal slot 46 which forms at its closed end 47 an enlarged preferably arcuate opening 48. The side edges of the collar portion 43 and adjacent portions of the extensions 44, 45 are preferably inwardly curved as indicated at 49, 50. Said scarf 42 may also be provided at the corners 51, 52 of the collar portion 43 with loops 53, 54 sewed to the underside of the scarf. A detailed view of the corresponding portion of the scarf shown in Fig. 1 is illustrated in Fig. 1a wherein the underside to which the loop 41 is sewed, is indicated by the numeral 55. The upper face of the scarf of Fig. 1 is indicated by the numeral 56, and that of Fig. 2 by the numeral 57.

Fig. 3 represents either scarf of Fig. 1 or Fig. 2 with the extensions provided with the knots 58 formed out of said extensions.

40 Figs. 4, 5 and 6 show major positions in which the scarf may be worn. For sake of simplicity, let it be assumed that the scarf of Fig. 1 is now being described in its application. In Fig. 4 the collar portion 31 is shown as a bib, whereas in 45 Fig. 6 the same is shown as a collar. In Fig. 5 collar portion 31 is shown as being retained by belt 60 of a dress 61 and the extensions 33, 32 are straps extending upwardly and draped over the shoulders of the wearer.

50 As it may be easily realized, extensions 32, 33 may be arranged over the shoulders of the wearer, draped joined together at various parts of the wearer's body, such as sides, back and neck either by knot or knots and/or pin or clasp.

55 Extensions 32, 33 may be tied or looped over

at the rear of the wearers' neck or brought in front of the wearer's neck in looped condition.

The extensions 32, 33 with knots 58 may form shoulder straps which are threaded through loops 38, 39 and then tied together by a bow knot at the wearer's back.

The scarf of Fig. 3 and its disposition is adapted particularly for beach wear.

Any suitable fabric may be employed for the scarf, particularly a material which can be easily draped and provides a reasonable stretch. This material may have one or more colors or differently colored facings. The proportion between the collar and extension portions may be varied, as desired, however, it has been found that in a scarf of forty-eight to fifty inches in total length, a collar of about seven to nine inches in length to extension length of about forty-one to forty-three inches gives satisfactory results and provides an unusual number of variations in draping and styles. It is preferable to provide extensions of a length such as to extend below the waist or corresponding to the average length of dress. In some cases, the scarf may be so arranged as to give the appearance of being a part or parts of a dress on which it is placed, adding attractively to the coloring and aesthetic effect of the dress. The width of both extensions may vary within certain suitable limits. However, a total width of about eighteen to twenty inches for both extensions together with the slot therebetween, the latter being about one-half to one inch wide, is preferred in order to make the apparel transformable from said scarf to fit average figures and sizes. The width of the collar or top portion is about seventeen inches, whereas the width of both extensions together should be sufficient to cover substantially the whole area of the front of wearer's body.

In some cases it has been further found that a proportion of about one to three between the length of the collar or unslotted end or top portion and the length of each of the extensions

may be sufficient to obtain quite a number of styles.

Although the above improvements relating to wearing apparel have been described with considerable detail and with respect to certain particular forms of the invention, it is not desired to be limited to such details since changes and modifications in the form, arrangements, proportions and sizes thereof may well be made without departing from the spirit and scope of the invention is its broadest aspect.

Having thus described the invention, what is claimed as new and desired to be secured by Letters Patent, is:

1. A scarf or the like comprising an oblong piece of material slitted for the major part of its length providing two extensions and an unslotted part having at one end thereof a transverse edge, each of said extensions being at least three times as long as said unslotted part, and loops located adjacent said transverse edge near opposite corners thereof, said extensions being adapted to be threaded through said loops when wearing said scarf.

2. A scarf adapted to be converted into a garment part to be worn on a human body comprising an elongated piece of fabric of substantially rectangular shape, said piece of fabric being slit from one end along the center line in lengthwise direction, said slit extending towards and terminating short of the other end of said piece thus providing an unslotted part and two extensions projecting from the unslotted part, the length of said unslotted part and that of each of said extensions being in a ratio of at least 1 to 3, the length of said extensions being such as to extend below the waist of the wearer's body, the combined width of both said extensions being sufficient as to cover substantially the whole area of the front of the wearer's body.
